UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A HOLDER FOR LAMP-FOUNTS.

SPECIFICATION forming part of Design No. 21,723, dated July 19, 1892.

Application filed June 20, 1892. Serial No. 437,382. Term of patent 3½ years.

To all whom it may concern:

Be it known that I, FRANZ YOKEL, of Meriden, in the county of New Haven and State of Connecticut, have invented a new Design for a Holder for Lamp-Founts; and I do hereby declare the following, when taken in connection with accompanying drawing and the letters of reference marked thereon, to be a full, clear, and exact description of the same, and which said drawing constitutes part of this specification, and represents a perspective side view.

This invention relates to a design for a holder for lamp-founts; and it consists in the configuration and ornamentation as shown in the accompanying illustration.

In outline horizontally the holder is represented as circular in shape. Vertically the sides spring from the bottom center, curving

outward, and thence swelling upward and inward, with a flaring neck above. The surface is represented as ornamented with rococo-work, the edge around the fount represented as bordered by a series of ornamental scallops, with an upwardly-projecting leaf between the scallops, and as shown in the accompanying illustration.

I claim—

The design for a lamp-fount, as herein shown and described.

In testimony whereof I have signed this specification in the presence of two subscribing witnesses.

FRANZ YOKEL.
